TARGET RANGE

Everett Leslie Dreyer, Chicago, Ill., assignor to
 A. B. T. Manufacturing Corp., Chicago, Ill., a
 corporation of Illinois

Application April 27, 1940, Serial No. 331,965

7 Claims. (Cl. 273—105.2)

This invention relates to amusement apparatus and has as its principal object the provision of improvements in a target range wherein target elements are fed onto runways to gravitate variously across the aiming range and, when struck by a missile, are dislodged from the runways and returned to a feeding mechanism which automatically restores the target members for reuse.

Viewed from another aspect, it is an important object of the invention to provide target apparatus especially suited for use with an air gun, although not restricted to such use, and to provide certain novelty effects in the movements of target members across the aiming range and in the collection and restoration of target elements which are dislodged by being struck.

A further and more particular object is the provision of an aiming range having a plurality of alternately inclined target runways and means for elevating target discs from a spent condition at the bottom of the runway system to a starting position at the top thereof, the discs being adapted to be struck by pellets or missiles from an air gun or the like and dislodged from the runway in a manner which lends a novel and attractive character to the device.

Still another object is the provision of target elements in the form of rigid discs adapted to roll along the runways and means on the runways for effectuating positive and vigorous movement of the target elements from the runways when struck as aforesaid.

A still further object is the provision of means for collecting the discs after the same are dislodged from the runways and stacking them to be picked up one at a time by an elevating or conveying device for restoration to starting position.

Other objects, advantages and novel aspects of the invention reside in certain details of construction as well as the cooperative relationship of the component parts of the illustrative embodiment described hereinafter in view of the annexed drawing, in which:

Fig. 1 is a front elevation of the shooting range;

Fig. 2 is a perspective of the target structure of the range;

Fig. 3 is a fragmentary vertical section to enlarged scale of the target collecting and return means, along lines 3—3 of Fig. 2;

Fig. 4 is an enlarged sectional detail of the runway structure, looking in the direction of lines 4—4 of Fig. 2;

Fig. 5 is an enlarged vertical sectional detail of the disc feeding means and conveyor, taken along lines 5—5 of Fig. 2;

Fig. 6 is another vertical sectional detail of the disc feeding structure looking in the direction of lines 6—6 of Fig. 5.

In its general aspects, the target range shown in Fig. 1 includes a suitable housing or hood 10 provided with inwardly sloping sidewall portions 11 converging toward the back of the range in 10 which there is situated the target panel 12. At the front of the range there is provided a table portion 13 upon which the aiming device or gun 14 is disposed when not in use.

Gun 14 is preferably an air gun adapted to 15 shoot relatively small pellets or BB shot, a gun suitable for use in the novel arrangement being described and claimed in my copending application, Serial No. 312,881, it being understood, however, that the novel target range apparatus is 20 adapted for use with any type of projectile-firing gun. The general description of the range is completed by pointing out that the target means consists of a plurality of target discs 15 which are automatically caused to roll down opposite- 25 ly inclined runway means across the panel 12, the arrangement being such that whenever the marksman succeeds in striking one of the target discs the same will be violently dislodged from the runway to give a positive and novel indica- 30 tion of a hit, dislodged discs being collected and restored for reuse in the device.

As seen in Fig. 2, the target structure itself includes the panel 12 mounted at an inclination of approximately seventy degrees to the horizontal 35 (Fig. 3 also), and mounted on the front face of this panel are the several runway strips 16, the same being preferably constructed of metal and of a width greater than the width of the metallic target discs 15 (Fig. 4). The runway strips 40 are secured to the panel by means such as the screws 16a, and between the panel and the runway strips is positioned a metal backing plate 12a, and in addition there is disposed between each runway strip 16 and the metal backing plate 45 12a, a ledge strip 17 having an upper portion 17a extending above the runway level of strip 16 so as to space the target discs 15 from the metal backing plate to reduce friction during gravitating movement along the several runways. 50

The ledge strips 17, and particularly the upper portions 17a thereof, have an additional important function in that they greatly enhance the reaction of the discs 15 in leaving the runway when struck by a pellet, especially at levels 55

above the top edges of the ledge portions 17a.

The upper end portion 16b of the first runway terminates opposite a feeding or loading opening 18 in a sidewall member 19 of the target panel, and the lower end 16c of this portion of the runway terminates above the upwardly curved upper end portion 16d of the next lowest runway strip, there being any number of these intermediate strips dependent upon the size of the installation, and the lower end portion 16e of the lowermost strip terminating in space on the panel above a downwardly inclined collecting or return apron 20 (Fig. 3 also).

The lowermost edge portions of the apron are pitched downwardly as at 21 to direct discs into a return channel 22, the bottom portion 23 of which is inclined from left to right (Fig. 2) across the target panel and leads into a discharge opening 24 in the side member 19 opposite a stacking device. The arrangement, as illustrated in Fig. 3, is such that the discs 15, when struck by a pellet, are violently dislodged from the runway 16 and follow variously the dotted-line movements until they fall upon the downwardly inclined apron from which they are gravitated into the return runway 22 for delivery to the stacking and return feed means.

The return stacking and feeding means is generally indicated at 25 in Fig. 2 and includes, as shown in the sectional view of Fig. 6, a trough-shaped structure 26 situated at the end of the exit 24, the member 26 having a downwardly pitched upper face 27 (Fig. 5), the lowermost edge portion of which is opposite a face of a feeding belt 28, the arrangement being such that the discs 15 in emerging from the return runway exit 24, drop into the yoke portion 26a of the member 26 and are gravitated by the downwardly inclined face portion 27 thereof to lie against the lower portion of the belt 28, there being room enough in the stacking means to accommodate a plurality, for example, four, of the discs 15, stacked one against the other in the manner illustrated in Fig. 5.

Means for restoring the target discs to the upper reaches of the runway includes the belt 28 mounted as aforesaid to be trained over pulleys 29 by a motor 30 provided with suitable speed-reducing means 31, there being a plurality of cleats or target engaging means 32 fixed to the outer face of the conveyor web or belt 28, which is trained in a clockwise direction, as seen in Figs. 2 and 5, to move the cleats around and up beneath the lowermost target disc 15a of the stack as said disc bears against the face of the web, the cleats 32 being thin enough so that they will pick up only one disc, the inclination of the web 28 being adequate to permit the disc to rest with its face thereagainst for transport to a position opposite the feeding or loading opening 18, and the individual cleats 32 being pitched toward the opening 18 so that as the conveyor web moves upwardly, the left-hand edge of the disc will ride against the sidewall member 19 until the disc is brought opposite loading opening 18, whereupon the disc will gravitate onto the upper end portion 16b of the upper run of the runway structure and begin its downward movement.

A feature of the invention resides in the fact that the feeding means, and particularly by spacing of the cleats 32 and regulation of the speed of the belt, may be made to release the target discs in such manner that there will be a disc on each runway section 16 during a given period 75 in which the marksman may shoot at all of the

discs and make a score, the reward value of which is predicated, for example, upon the order in which he dislodges the discs from their respective runway sections during this period.

It will be apparent that the feeding mechanism 5 may be adjusted to permit the discs to traverse the entire runway system one at a time or in close succession, and that the discs may be colored or otherwise identified to set up variable scoring arrangements depending upon the order 10 in which they are fed onto the runways and the order in which they may be struck during traversal of the runways, it being apparent that individually colored or identified discs may be interchanged in the order in which they will be 15 stacked in the feeding means in a manner dependent upon the order in which they are struck and dislodged from the runways, so that a variety of combinations is possible. Other specific arrangements of this sort will occur to those skilled 20 in the art.

In the operation of the device of Fig. 1, the gun 14 may be considered as of the repeating variety, loaded with a predetermined number of shot, and the motor means 30 may be considered to be set into operation by closing of switch means 35 conveniently situated on the range structure so that the target discs 15 will be elevated by the upwardly moving cleats 32 for release in succession to traverse the runways 16 30 at a rate which will enable the marksman to train the gun thereon, each disc which is struck being dislodged from the runway and returned by the means 20—22—23 to the stacking yoke 26 at the bottom of the elevating or feeding device. 35 A large number of shot will also find their way into the return runway 22 and gravitate with the discs into the stacking means, and in order to remove the shot, the yoke structure 26 is provided with a grooved or relieved portion 26a (Figs. 40 5 and 6) which permits the shot to roll beneath the stacked discs and into some form of collecting receptacle.

The various advantages and objects of the invention may be accomplished by modifications of 45 the particular embodiment specifically described herein, and it is intended that the appended claims shall include all equivalent arrangements fairly coming within their call.

Having thus described my invention, what I 50 claim as new and desire to protect by Letters Patent is:

1. In a target range, a series of alternately inclined superposed runways down which a target element may roll, means for collecting target 55 elements from the lowermost runway and elevating the same onto the topmost runway, and means providing a ledge above the rolling surface on each runway and against which a side of the target element may bear in passing down the 60 runways.

2. A target device comprising, in combination, a backing member in a plane at an inclination to the horizontal, a plurality of oppositely inclined runways on said backing member and 65 adapted to guide a rolling target element in gravitating movement from the topmost to the lower most runway back and forth across an aiming range, and ledge means extending above the rolling surface on each runway for spacing the target element from said backing member during movement down the runways.

3. A target apparatus comprising, in combination, a backing member tilted from the vertical, a plurality of alternately inclined runway 70 75

- strips on the backing member and adapted to guide a rolling target element for gravitating movement from the topmost to the lowermost strip, each runway strip being provided with a 5 spacing member extending above the rolling surface thereon to space said target elements from said backing member during movement down the runway strips, said target elements being dislodged from said strips by engagement therewith 10 of a projectile, means for stacking target elements in a region adjoining the lowermost runway strip, and means for guiding target elements dislodged from said strips or gravitating from the lowermost strip into operative engagement 15 with said stacking means, and mechanism for removing target elements one at a time from stacked condition by said stacking means to the uppermost runway strip for gravitation as aforesaid.
- 20 4. Target apparatus comprising, in combination, an inclined back stop, a plurality of alternately inclined runway strips on said back stop with the lower end of one terminating above the upper end of another to guide a target disc 25 in rolling movement from the upper end of the uppermost runway strip off the lower end of the lowermost strip, means for spacing a target disc from said back stop during rolling movement as aforesaid, the discs being adapted to be dislodged 30 from the strips when struck by a missile, a return runway beneath the lowermost runway strip and adapted to gravitate a disc into a feeding position, said runway being positioned to receive a disc gravitating off the lowermost strip, means 35 for receiving discs dislodged by missiles as aforesaid and guiding the same into said runway, and means for transporting said discs from said feeding position onto the upper portions of the uppermost strip for gravitating movement down 40 the strips as aforesaid.
5. Target apparatus comprising, in combination, an inclined back stop, a plurality of alternately inclined runway strips on said back stop with the lower end of one terminating above the upper end of another to guide a target disc in 45 rolling movement from the upper end of the uppermost runway strip off the lower end of the lowermost strip, ledge means disposed above the rolling surface of the strips for spacing upper portions of the target disc from said back stop during rolling movement as aforesaid, the discs being adapted to be dislodged from the strips when struck by a missile, a return runway be- 50
- neath the lowermost runway strip and adapted to gravitate a disc into a feeding position, said runway being positioned to receive a disc gravitated off the lowermost strip, means for receiving discs dislodged by missiles as aforesaid and guiding the same into said runway, and means for transporting said discs from said feeding position onto the upper portions of the uppermost strip for gravitating movement down the strips as aforesaid. 5
6. Target apparatus comprising, in combination, an inclined back stop, a plurality of alternately inclined runway strips on said back stop with the lower end of one terminating above the upper end of another to guide a target disc in 15 rolling movement from the upper end of the uppermost runway strip off the lower end of the lowermost strip, means for spacing a target disc from said back stop during rolling movement as aforesaid, the discs being adapted to be dislodged 20 from the strips when struck by a missile, a return runway beneath the lowermost runway strip and adapted to gravitate a disc into a feeding position, said runway being positioned to receive a disc gravitating off the lowermost strip, means 25 for receiving discs dislodged by missiles as aforesaid and guiding the same into said runway, and means including a circuitously moving conveyor element with disc engaging means thereon and arranged to move said disc engaging means beneath a disc at said feeding position and elevate the disc into position opposite the upper regions of the uppermost runway strip, said disc engaging means being inclined toward the uppermost runway strip, whereby a disc may be gravitated onto said uppermost strip when elevated opposite thereto, and means for maintaining a disc in engagement with said disc engaging means until the disc is elevated as aforesaid. 30
7. In a target device of the class described including a back stop mounted at an inclination to the horizontal and a downwardly inclined runway strip on said back stop and down which a target disc is adapted to roll across an aiming range, the combination with said strip of spacing means extending above the rolling surface thereof to maintain the major upper portions of the disc in spaced relation to said back stop in rolling down the strip, said discs being adapted to be dislodged from the strip by reaction with 45 said spacing means when struck by a missile. 50

EVERETT LESLIE DREYER.
